UNITED STATES PATENT OFFICE

95,095

DESIGN FOR A GAME DEVICE

Frank C. Wachs, Milwaukee, Wis.

Application January 19, 1935, Serial No. 54,933

Term of patent 7 years

To all whom it may concern:

Be it known that I, Frank C. Wachs, a citizen of the United States, residing at Milwaukee, in the county of Milwaukee and State of Wisconsin, have invented a new, original, and ornamental Design for a Game Device, of which the following is a specification, reference being had to the accompanying drawing, forming part thereof.

I claim:

The ornamental design for a game device, as shown.

FRANK C. WACHS.
